UNITED STATES PATENT OFFICE

97,685

DESIGN FOR AN ENSEMBLE DRESS

Emil Schwartz, New York, N. Y.

Application November 2, 1935, Serial No. 59,331

Term of patent 3½ years

To all whom it may concern:

Be it known that I, Emil Schwartz, a citizen of the United States of America, residing in Manhattan, county of New York, and State of New York, have invented a new, original, and ornamental Design for an Ensemble Dress, of which the following is a specification, reference being had to the accompanying drawing, forming part thereof, wherein,

The cross hatched and parallel lines on the sleeves, neck-line and extending down the front of the jacket member of the ensemble, represent quilting.

The dotted lines on the collar of the dress member of the ensemble represent stitching.

I claim:

The ornamental design for an ensemble dress, substantially as shown, and described.

EMIL SCHWARTZ.
